UNITED STATES PATENT OFFICE.

OTTO A. HEPPES, OF LA GRANGE, ILLINOIS, ASSIGNOR TO THE FLINTKOTE COMPANY, OF BOSTON, MASSACHUSETTS, A CORPORATION OF MASSACHUSETTS.

ROOFING.

Application filed September 8, 1923. Serial No. 681,574.

This invention relates to roofing more particularly of somewhat flexible material such as is commonly made of fibrous sheet material saturated with waterproofing material, as asphalt, and coated with high melting point asphalt, with or without a surfacing of granular material such as crushed slate. When such material is laid in superposed overlapping courses any depending tabs or projections exposed to the weather are liable to become raised from the roof as by wind or accidental curling or warping of the material, impairing the appearance of the roof and if pronounced, its weatherproofing capabilities also. The tabs or projections are also liable when raised to be torn off or otherwise damaged. This action is particularly liable to occur when comparatively large shingle units are being used, as for example, when square shingles are laid diagonally on the roof exposing to the weather all but comparatively narrow portions along their upper converging edges.

According to the present invention, therefore, each shingle is so formed that a portion of its depending corner may be folded backwardly under the adjacent edge of a shingle of an underlying course.

For a more complete understanding of this invention, reference may be had to the accompanying drawings in which

Figure 1 is a plan of a shingle formed according to this invention.

Figure 2 is a fragmentary plan of a roof showing the shingles of Figure 1 laid thereon.

Figure 3 is an enlarged detail showing the manner of folding under the edges of adjacent shingle portions cut from the corner of the superposed shingle.

Referring to these drawings, 1 indicates a shingle element of polygonal form, herein shown as square, having the upwardly converging sides 2 and 3 and the downwardly converging sides 4 and 5. The depending corner portion as 6 of each unit is cut away to form a pair of tabs 7 and 8, the tab 7 forming a continuation of the marginal portion 5 and the tab 8 being offset inwardly from the edge 4, but extending parallel thereto. The tabs are so formed by a cut 9 parallel to the edge 5 extending inwardly to the outer edge of the tab 8, a cut 10 parallel thereto defining the inner

edge of the tab 7 and the outer end of the tab 8, and a cut 11 parallel to the side 4 defining the inner edge of the tab 8. The tab 7 may thus be bent along the line 12 to underlie the adjacent marginal portion along the side 5 and the tab 8 may be bent along the line 13 to underlie a portion back from the edge 4 but parallel thereto. The lines of bending 12 and 13 of the tabs 7 and 8, respectively, are determined respectively by the lines of cut 9 and 11, constituting substantially a continuation thereof and forming shoulders with the edges of the respective tabs 8 and 7. The line of cut 11 also spaces the tab 7 from its inner extremity, allowing the bending of the tab without tearing of the material at the extremity.

The shingles are laid as shown in Figures 2 and 3 in diagonally disposed courses, the corner having the tabs 7 and 8 being downwardly presented, these tabs 7 and 8 being bent backwardly then folded under to enclose the edges 4 and 5 of a pair of shingles of an underlying course adjacent their upper portions. The shingles are attached to the roof by fasteners such as nails driven therethrough along the margins adjacent the upper edges 2 and 3 which will be overlapped by the succeeding course of shingles, hence the margins along the upper edges 2 and 3 are closely tied down to the roof, and as the tabs 7 and 8 of the shingles of the succeeding course engage the units of the preceding course adjacent these margins, the lower corners of each unit are also held firmly down against the roof. It will be noted that each tab is of less width than the cut away portion showing when the shingles are assembled so that the lines of bending of the tabs are clearly defined. This construction facilitates bending back of the tabs on the proper lines and avoids danger of tearing the material at the apex of the cut out when the bending is effected.

Having thus described an embodiment of this invention it should be evident that various changes and modifications may be made therein without departing from its spirit or scope as defined by the appended claims.

I claim:

1. A roofing unit having a square piece of sheet material having one corner cut to form a tab forming a continuation of one marginal portion extending toward the apex of

said corner, and a tab offset inwardly from the adjacent side edge and substantially parallel thereto and extending toward said one marginal portion.

2. A roofing unit having converging side edges having cuts at the apex thereof to form a cut-away portion and a tab of less width than said cut-away portion, said tab being foldable back to engage behind the edge portion of an adjacent unit when laid, one of the cuts being substantially parallel to one of the said edges of the unit and forming a shoulder with an edge of the tab, thus determining the line of fold of said tab.

3. A roofing unit having converging side edges having cuts at the apex thereof to form a "cut-away" portion and tabs each of less width than said cut-away portion, said tabs being foldable back to engage behind the edge portions of adjacent units when laid, certain of said cuts forming shoulders with the edges of each of the tabs and thus determining the lines of fold of said tabs.

25 4. A roofing unit having converging side edges having cuts at the apex thereof to form a cut-away portion, and tabs each of less width than said cut-away portion, said tabs being foldable back to engage behind the edge portions of adjacent units when laid, cuts substantially parallel to the side edges of said unit forming shoulders with

edges of the tabs and thus determining the lines of fold of said tabs.

5. A roofing unit having converging side edges having cuts at the apex thereof to form a cut-away portion and a tab of less width than said cut-away portion, said tab being foldable back to engage behind the edge portion of an adjacent unit when laid, one of the cuts having an extremity within the unit and forming a shoulder with an edge of the tab, thus determining the line of fold of said tab and spacing it from its inner extremity. 45

6. A roofing unit having converging side edges having cuts at the apex thereof to form a cut-away portion, and rectangular tabs adjacent to said cut-away portion and foldable back with their edges substantially parallel respectively to said converging edges of the unit. 50

7. A roofing unit having converging side edges having cuts at the apex thereof to form a cut-away portion, and rectangular tabs adjacent to said cut-away portion and foldable back on one of their shorter sides, said tabs having their longer sides substantially parallel respectively to said converging sides edges of the unit. 60

In testimony whereof I have affixed my signature.

OTTO A. HEPPES.
